EVAPORATIVE COOLER CABINET WITH WATER DISTRIBUTING MEANS

William A. Marshall, Carl V. Alexander, and Arthur C. Keller, Dallas, Tex., assignors to Dearborn Stove Company, Dallas, Tex.

Application May 9, 1955, Serial No. 507,081

4 Claims. (Cl. 299—58)

This invention relates to evaporative coolers and it has particular reference to the water distributing means for such coolers.

The principal object of the invention is to provide, in an evaporative cooler cabinet, a means to insure uniform distribution and flow of water into the filter mats and, with this in view, to provide a water supply trough pivoted at its midsection for tilting displacement in the cabinet so that either end of the trough can be raised and lowered to level the same and thus correct conditions where the cabinet itself is not or cannot be mounted on a level plane.

Another object of the invention is to provide a water distributing trough for an evaporative cooler cabinet, one of which is suspended from the top of each of three louvered side panels of the cabinet by means of a bracket affixed to the trough at its midsection and pivotally engaged at its upper end with the side panel, said bracket, in turn, being supported by a set screw which is movable in a horizontal slot in the panel below the pivotal engagement between the bracket and panel and which secures the trough in adjusted positions. Moreover, the trough is equipped with angular end plates, at least one of which carries a laterally extending pin slidable in an angular slot in the adjacent wall of the cabinet and by which the trough is manually moved to compensate for any unevenness in the cooler cabinet itself.

Other objects will appear as the description proceeds when considered with the annexed drawing, wherein:

Figure 1 is a rear perspective view of an evaporative cooler cabinet shown mounted in a window and reveals the type of cooler in which the invention is designed to function.

Figure 2 is a fragmentary perspective view of the cooler cabinet showing the trough and adjusting means of the invention mounted therein.

Figure 3 is an enlarged, fragmentary perspective view of the trough showing one of the water outlet openings therein, and

Figure 4 is an end elevational view of the trough, partly in section, showing a slight modification in the pivotal suspension of the trough.

Continuing with a more detailed description of the drawing, reference numeral 10 denotes generally an evaporative cooler cabinet of more or less conventional design. This type of cooler is usually mounted adjacent an opening, such as a window 11, and a duct 12 conveys air into the building after having been cooled by its passage through wetted mats (not shown) suspended in the cabinet 10 adjacent the louvered side walls 13 of the latter, there being mounted within the cabinet a conventional blower by which the air is influenced through the mats and duct 12. The cabinet 10 is usually suspended by chains 14 connected at one end to the top of the cooler cabinet at their opposite ends to the wall of the building above the window 11 or on each side thereof. The chains 14 are adjustable in length by turnbuckles 15. Any suitable means, such as threaded rods or bolts 16 may be used for adjustably

2

supporting the lower portion of the cabinet 10 from the building wall below the window 11.

The foregoing relates to features which are common to evaporative cooler cabinets produced by different manufacturers. However, the present invention anticipates the water trough and its adjusting means which will be fully explained in the following description.

Each of the three walls 13 of the cabinet 10 is provided with vertical rows of horizontally spaced louvers

10 17. These rows of louvers terminate short of the tops of the walls, as illustrated in Figure 2, leaving a blank area 18 adjacent to the tops of the sides or walls 13 and co-extensive in width thereof. Behind these wall areas 18 are mounted water distributing troughs 19.

15 Each trough 19 is fabricated from sheet metal and formed into a substantially V-shape, as shown, having closed ends 20. Along either side of the trough, but preferably on the side 21 thereof adjacent the cabinet wall 13, there is provided a horizontal row of water outlet or drainage openings. Each opening is in the form of a slot 22 which extends upwardly from a dimple 23 pressed inwardly from the trough wall 21. This arrangement breaks surface tension and insures uninterrupted flow of water through the openings at all times.

20 25 Each of the cabinet walls 13 has an inwardly turned, horizontal flange 24 along its upper edge and each flange 24 has a slot 25 midway between its ends adjacent the wall 13. This slot receives a tab 26 formed integrally with the top edge of a bracket 27 constituting a part of the supporting means for the trough 19 and by which the trough is made capable of tilting displacement.

25 30 The bracket 27 is formed with a portion 28 which is in flush parallelism with the outer wall 21 of the trough and is spot welded thereto. The bracket breaks outwardly at 29 and downwardly at 30 into vertical parallelism with the panel 13. A speed nut 31 in the form of a U-shaped member straddles the lower edge of the portion 30 of the bracket 27 and has matching holes 32 and 33 which are in register with a hole 34 in the bracket portion 30 and a horizontal slot 35 in the panel 13.

35 40 A set screw 36 extends freely through the slot 35 of the panel 13, the hole 33 in one leg of the speed nut 31, the hole 34 in the bracket portion 30 and the rear end of the set screw is threaded in the hole 32 in the inner leg of the speed nut 31.

45 50 The trough 19 actually pivots about the point where the tab 26 engages the slot 25 in the flange 24 of the panel 13, as permitted by the angular shoulders $a-a$ on opposite sides of the tab 26 and the horizontal slot 35 in the panel. When the trough is made level, the screw 36 is turned, thereby clamping together the legs of the speed nut 31, the bracket portion 30 and the panel 13 to preclude displacement of the trough from adjusted position.

55 60 In Figure 2, the dotted lines above the plane of the trough indicate tilted positions of the latter on each side of the centrally located fulcrum point. To provide for manual adjusting of the trough, the panel 13 has an oblique slot 37 opposite one or each end of the trough 19. Actually, only one such slot is required but two are shown. To each end of the trough is spot welded an angular plate 38 and to the angle 39 of the plate is welded a pin 40 which extends outwardly through the slot 37 in the panel 13. The slot 37 is angled to compensate for tilting displacement of the ends of the trough as the latter is oscillated about the axis afforded through the engagement of the tab 26 in the slot 25. After loosening the set screw 36, the trough is brought into level position by simply pushing up or down on the pin 40 and then, by holding the pin in the position it is in when the trough is leveled, the set screw is tightened to secure the trough in the level position, thus to insure uniformity in water flow

into the filter mats of the cooler. If desired, a pin corresponding to the pin 40 may be similarly attached to the angle of the opposite end plate 38 and engaged in the slot 41 in the side of panel 13 opposite the slot 37. (Figure 1), although dual slots and pins are not generally necessary.

There are two places where tilting displacement of the trough is limited, one being in angular shoulders *a*—*a* of the bracket 27, receding from each side of the tab 26. (Figure 2) while the other is in the length of the slot 35 in panel 13 which limits the travel of the set screw 36. This is actually where the degree of tilt is controlled.

Leveling of the water troughs of evaporative coolers has heretofore been accomplished by yieldingly or pivotally securing the trough at one end to a wall of the cooler cabinet, permitting the opposite end to move in a vertical plane, with provision for securing the movable end of the trough when adjustment has been accomplished. The advantages of center adjustment of the trough are that leveling of the latter is more positive and requires but half the end displacement necessary for the adjustment of the end suspended troughs, which, in certain cases, cannot be moved sufficiently for leveling, particularly where the louvers in the wall panels extend above the bottom of the trough which requires or should require that the tops of the filter mats extend equally as high, leaving little space for trough adjustment. In the present invention, sufficient space is provided, by virtue of the blank space 18, above the louvers 17 and the mats for unrestricted adjustment of the trough 19 although, as stated, it requires only half the movement to level this trough as is necessary to level a trough mounted at one end.

In Figure 4 is shown a trough and adjusting means identical to that shown in Figures 1 to 3 except for the fact that instead of the pivotal connection afforded by the tab 26 and slot 25, the trough is pivotally suspended by means of a rivet, stud or machine screw 42, the latter being shown in the drawing.

Aside from the reference numeral 42 denoting the screw, the same reference numerals are used in Figure 4 to denote identical corresponding parts in Figures 1 to 3.

In the modified form of pivotal suspension for the trough 19, the inturned flanges 24 at the tops of the wall panels 13 are dispensed with and the pivot member or screw 42 is extended through matching apertures in the tab 26 and panel 13 and is secured as by threading the aperture in the panel, by soldering, peening or by any other means, depending on the nature of the pivot member 42.

The trough 19 is adjusted by its rotation about the pivot member 42, by means of the pin 40, permitted by the horizontal slot 35 through which the set screw 36 extends and which enters matching holes 33 and 32 in the legs of the speed nut or equivalent member 31 and the hole 34 of the portion 30 of the bracket 29. The screw 36 is threaded into the hole 32 of the member 31, hence tight-

ening of the screw will bring the legs of the member 31, the depending portion 30 of the bracket and the panel 13 into close union to secure the trough in adjusted position.

Manifestly, the construction as shown and described is capable of some modification and such modification as may be construed to fall within the scope and meaning of the appended claims is also considered to be within the spirit and intent of the invention.

What is claimed is:

1. In an evaporative cooler cabinet having a louvered wall, a water distributor comprising a trough supported at the top of said wall for tilting displacement about a horizontal axis disposed midway between the ends of said trough, a bracket affixed to said trough at its midsection and having pivotal connection with said wall at its top, a set screw extending through said wall below said pivotal connection and engaging said bracket to hold said trough in adjusted positions and manually operable means carried by one end of said trough and extending through a slot in said wall for tilting displacement of said trough.

2. In an evaporative cooler cabinet having a wall provided with louvers terminating at a point spaced below the top of said wall, a water distributor comprising a trough disposed below the upper edge of said wall inwardly of the unlouvered portion thereof, a bracket affixed to said trough at its midsection and having a portion thereof extending above said trough and pivotally engaging said wall adjacent its top edge and adapted to hold said trough for tilting displacement, means below the pivotal connection between said trough and wall for clamping, engaging said bracket to hold said trough in adjusted positions and manually actuated means affixed to said trough and accessible exteriorly of said wall for tilting said trough about said pivotal connection.

3. In an evaporative cooler cabinet having a louvered wall, a water distributing trough disposed above the louvers in said wall, a bracket affixed to said trough at its midsection and having a downwardly and an upwardly extending portion, means attaching said upwardly extending portion to said wall to define a fulcrum about which said trough is tiltable, and means extending through said wall and engaging the downwardly extending portion of said bracket to hold said trough in adjusted positions.

4. The structure of claim 3, and a pin mounted on one end of said trough and engaging a slot in said wall above said louvers to effect manual tilting displacement of said trough about said fulcrum.
